ELECTRICALLY POWERED CHURN

William E. Gundelfinger, House Springs, Mo., assignor
to The Dazey Corporation, St. Louis, Mo., a corpora-
tion of Missouri

Application September 7, 1956, Serial No. 42,868

Term of patent 7 years

(Cl. D23—1)

Fig. 1 is a top plan view of an electrically powered churn embodying my new design;

Fig. 2 is a front elevational view thereof; and

Fig. 3 is a rear elevational view thereof.

The side elevational views as seen from the left and right of either Fig. 2 or 3 are substantially like the front view shown in Fig. 2 without the openings.

I claim:

The ornamental design for an electrically powered churn, substantially as shown and described.
